US00D732437S

(12) **United States Design Patent**
Yang et al.

(10) **Patent No.:** **US D732,437 S**
(45) **Date of Patent:** **** Jun. 23, 2015**

(54) **SCOOTER**

(71) Applicant: **Kwang Yang Motor Co., Ltd.**,
Kaohsiung (TW)

(72) Inventors: **Chu-Chung Yang**, Kaohsiung (TW);
Chuan-Chun Su, Kaohsiung (TW);
Kuo-Feng Huang, Kaohsiung (TW)

(73) Assignee: **Kwang Yang Motor Co., Ltd.**,
Kaohsiung (TW)

(**) Term: **14 Years**

(21) Appl. No.: **29/501,782**

(22) Filed: **Sep. 9, 2014**

(51) LOC (10) Cl. **12-11**

(52) U.S. Cl.

USPC **D12/110**

(57) **CLAIM**

The ornamental design for a scooter, as shown and described.

DESCRIPTION

FIG. 1 is a perspective view of a scooter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are for the purpose of illustrating portions of the scooter that form no part of the claimed design.

1 Claim, 7 Drawing Sheets
